UNITED STATES PATENT OFFICE.

LEVI I. BODENHAMER, OF KERNERSVILLE, NORTH CAROLINA.

CAR-COUPING.

SPECIFICATION forming part of Letters Patent No. 279,217, dated June 12, 1883.

Application filed August 21, 1882. (No model.)

To all whom it may concern:

Be it known that I, LEVI ISAAC BODENHAMER, a citizen of the United States, residing at Kernersville, in the county of Forsyth and State of North Carolina, have invented 5 certain new and useful Improvements in Car-Couplings; and I do hereby declare the following to be a full, clear, and exact description of the invention, such as will enable others skilled in the art to which it appertains to make 10 and use the same.

My invention has relation to car-couplings, particularly to that class which are intended to couple automatically as the cars come together; and my said invention consists, first, 15 in a novel provision at the mouth of the draw-head, whereby the coupling together of cars of equal height, or a high and low car, may be effected and the link guided into place without going between the cars, this being accomplished by a plate hinged to the lower front edge of the draw-head, said plate being made to fold back within the mouth of the draw-head as the cars come together, and adapted 20 to be thrown forward and lift the coupling-link upward, thus guiding it in place in the opposite draw-head; second, in a peculiar novel construction and arrangement of the device or means for holding the coupling-link 25 within the draw-head, said device or means being composed of a peculiar-shaped bar or latch-piece pivoted to the top front portion of the draw-head, provided with a seat at its lower rear portion, into which the coupling-link 30 rests and against which it draws, the rod upon which the gravitating coupling-bar or latch-piece is held having short rearwardly-extending arms attached thereto, which act as additional weights or levers to keep the coupling-link 35 bar or latch-piece down in place.

Referring to the drawings forming a part of this application, and in which similar letters of reference indicate like parts in the several views, Figure 1 will be found to represent a 45 vertical central longitudinal section and side elevation of my improved form of coupling and link-guiding device; Fig. 2, a detached view of the link-raiser, and Fig. 3 a detached view of the gravitating coupling-bar or latch-piece.

A is the draw-head, to the top interior front

portion of which is secured the latch-piece or bar B, for securing the link C within the draw-head. The draw-head A has the usual-shaped flaring mouth. Transversely through the interior front portion of the draw-head, just beneath the top wall thereof, passes a rod, b, upon which the latch-piece B is secured. This rod b is secured in a channel on the under surface of the top of the draw-head, which forms the 55 bearings thereof, and at each end of said rod are secured short rearwardly-extending arms, D D, with eyes d at their outer ends, which arms act as additional weights or levers to the coupling latch-piece, and form a means by 60 which to operate the coupling latch-piece to uncouple the cars.

Within the interior top portion of the draw-head is formed a recess or chamber, A', which receives the coupling latch-piece B, when said 70 latch-piece is in its elevated position. When down in place the lower end of the latch-piece rests in a recess, A'', in the lower part of the draw-head. By reference to Fig. 1 it will be seen that the means for holding the coupling-link in place—the "coupling latch-piece," as I term it—is formed with a straight front edge or face, a, which at the lower end terminates in a flat inclined end, a', which rests square upon the bottom of the recess formed in the 75 bottom of the draw-head. At the rear of the latch-piece is a projecting portion, a'', which, with the end portion a', forms a shouldered seat, against which the link has its bearings. The object of thus forming the coupling latch-piece is to provide a direct bearing thereon for the coupling-link, and to confine said coupling-link to its place upon the latch and prevent it 80 from slipping up against the top of the draw-head. By reason of this shouldered seat a' a'' 85 on the latch-piece B the draft is more direct and positive, and the tendency to break this piece is therefore diminished and the close and rigid coupling together of the cars better effected. When the coupling latch-piece is in position, with its end resting upon the recess in the 90 lower part of the draw-head, it will be seen that the top part of the projecting portion a'' rests about flush with or slightly within the recess formed in the top of the draw-head. Because 95 of this the coupling-link is prevented from slipping up or riding upon the latch-piece and

- wedging itself between the latch-piece and upper part of the draw-head; also, by reason of the recess formed in the top of the draw-head for the latch-piece and its pivot-bolt, the 5 parts are more out of the way and less liable to injury. So, also, by reason of the entire parts being protected or under shelter beneath the edge of the draw-head, the clogging of the parts by ice, dust, &c., is prevented.
- 10 To further add to the effectiveness of the apparatus and insure the entrance of the link within the draw-head, whether high or low cars come together, and without the necessity of going between the cars, the lower portion 15 of the mouth of the draw-head is provided with a link raiser and guide, G, Fig. 2, which consists of a plate, G, with slotted end g, secured upon a shaft, S, which passes transversely through the lower front edge of the 20 draw-head. This shaft has a handle, S', at one or both ends, by which the plate G is raised or lowered at the side of the car, and without going between the same. Thus danger of injury because of going between the cars to guide the 25 coupling-link is removed. At the lower part of the guiding-plate G is formed a stop, I, which strikes against the shoulder i on the draw-head and prevents the too far forward movement of the plate. The object of this 30 plate is to form a means whereby to guide the coupling-link into an approaching draw-head without going between the cars. This is accomplished by manipulating the handle S', which raises the plate G, and the link C, resting in the slotted end g, is carried upward any 35 desired degree, as is apparent. By reason of the link resting in the slotted plate, it is held straight or in line and prevented from swaying to one side.
- 40 Because of the form of the coupling latch-piece, secure bearing for the link is the result, and the parts are made strong, and not liable to become disarranged and clogged. Being within the mouth of the draw-head, the 45 parts are better protected from the action of the weather and accidents.

By reason of the recess in the bottom of the draw-head, which receives the lower end of the latch-piece, the coupling-link is prevented from getting beneath the end of said latch-piece and slipping past the same. In other words, accidental uncoupling of the cars because of the jolting of the latch-piece above the link is prevented.

Having thus described my invention, its operation, advantages, &c., what I claim as new, and desire to secure by Letters Patent of the United States, is—

1. In a car-coupling, the plate G, hinged to the lower front edge of the mouth of the draw-head, and adapted to fold back therein, having slots g g at its top end to receive the coupling-link, and a stop, I, to prevent its too far forward movement, combined with a handled pivot, S S', by which it is operated, and a 60 draw-head with inclined mouth, and shoulder i, to receive the plate G, as hereinbefore described, for the purposes specified.

2. In a car-coupling, in combination with the draw-head having recess A' in its top interior 70 surface and recess A² at its bottom, the coupling latch-piece B, pivoted to the top interior front end of the draw-head, with straight front face, a, tapered end a' a³, and rear shoulder, a², and pivot-bolt b, having arms D at each side of 75 the draw-head, for the purposes described.

3. The combination and arrangement, in a car-coupling, of draw-head A, having recess A' at its top and recess A² at its bottom, latch-piece B, with straight face a, tapered end a' a³, 80 and shoulder a², plate G, with slots g g at its top end and stop I at its bottom, handled pivot-bolts D d and S S', for operating the coupling latch-piece B and link-guiding plate G, respectively, as described.

In testimony whereof I hereto affix my signature in presence of two witnesses.

LEVI ISAAC BODENHAMER.
